UNITED STATES PATENT OFFICE.

JAMES R. MOORE, OF PITTSBURGH, PENNSYLVANIA.

VALVE-STEM LUBRICATOR.

1,373,346.

Specification of Letters Patent.

Patented Mar. 29, 1921.

Application filed February 27, 1920. Serial No. 361,909.

To all whom it may concern:

Be it known that I, JAMES R. MOORE, a resident of Pittsburgh, in the county of Allegheny and State of Pennsylvania, have 5 invented a new and useful Improvement in Valve-Stem Lubricators, of which the following is a specification.

The invention relates to intake and exhaust valves of internal combustion engines, 10 or in other words, to valves for controlling the flow of a carbureted mixture to, and the flow of exhaust from, the cylinders of such engines.

Because such valves are frequently quite 15 inaccessible, it is quite difficult to properly lubricate them, and in most engines no provision whatever is made for their lubrication. Due either to inadequate lubrication or to the lack of any lubrication, the valve 20 stems frequently become hot and so warp or expand that the stems stick in their surrounding sleeves and the valves fail to operate.

It is the object of the invention to provide 25 for valves of the character explained a simple and inexpensive, but at the same time efficient means for lubricating them.

The invention is illustrated in the accompanying drawing which shows in combined 30 vertical elevation and vertical sectional view a valve installed in an internal combustion engine.

Valves of the character contemplated herein 35 comprise a spindle 1, to one end of which there is attached a valve 2 adapted to co-operate with a valve seat 3 to control flow of either a carbureted mixture from a manifold 4 to the cylinder of the engine, or to control the flow of exhaust from the cylinder 40 to the manifold. The valve construction includes, also, a sleeve 5 within which the spindle 1 is mounted for longitudinal reciprocation, the sleeve 5 extending through the wall of the manifold 4 as indicated. 45 For holding the valve structure in its proper position and in such a manner that the structure may be readily disassembled and removed from the engine, the sleeve 5 is usually provided with a laterally extending 50 flange 6 adapted to bear upwardly upon the lower side of a lug or other member 7, cast integrally or otherwise attached to the engine. At the lower end of the spindle 1 there is a sleeve washer 8 held in its indicated 55 position by means of a pin 9 extending through a slot formed in the spindle. Be-

tween the washer 8 and the flange 6 there is a coil spring 15 adapted to urge the spindle 1 downwardly and hence to hold the valve 2 against the seat 3 and the flange 6 against 60 the member 7. Such valves are intermittently opened, as by means of a cam 10 attached to a cam shaft 11 and adapted to bear upon the bottom of the spindle 1.

To properly lubricate the spindle 1 so that 65 it may continuously slide freely within the sleeve 5, a lubricator is provided at the end of the sleeve. Such lubricator preferably comprises a casing 12 surrounding the spindle and containing a body of lubricant-absorbing material 13. Preferably, 70 the casing 12 extends upwardly above the lower end of the sleeve 5 and is provided at its upper end with an outwardly projecting flange 14 adapted to be held between the 75 upper end of the spring 15 and the lower face of the flange 6. The portion of the casing 12 above the lower end of the sleeve 5 constitutes an oil supply reservoir into 80 which lubricating oil may be inserted through a suitable opening 16.

In operation the oil from the reservoir in the upper end of the casing 12 is gradually absorbed by the lubricant-absorbing body 13, and is fed upon the spindle 1 as the spindle 85 is intermittently reciprocated by the cam 10. The lubricant thus fed upon the spindle, works upwardly between the spindle and the sleeve 5 and effectively lubricates the adjacent bearing surfaces of these members, with the result that the valve operates 90 freely and continuously. It has been found that with the construction illustrated in the drawing, sufficient lubricant may be stored in the lubricator to effectively lubricate the 95 valve for a period of from a week to ten days.

According to the provisions of the patent statutes, I have described the principle and operation of my invention, together with 100 the construction which I now consider to represent the best embodiment thereof. However, I desire to have it understood that, within the scope of the appended claims the invention may be practised by other forms 105 of construction than that particularly shown and described herein.

I claim as my invention:—

1. The combination with an internal combustion engine having a cylindrical bearing element, of a valve having a spindle mounted 110 for longitudinal reciprocatory movement

in said bearing, a lubricator casing surrounding said spindle and provided with an outwardly turned flange adjacent to the bearing element, a lubricator within and held by said casing at the end of said bearing element, and a single spring acting between said flange and said spindle to hold the valve closed and the lubricating casing in position.

10 2. The combination with an internal combustion engine, of a valve sleeve having an outwardly projecting flange, a valve having a spindle mounted for longitudinal reciprocatory movement in said sleeve, a lubricator

casing surrounding said spindle and provided with an outwardly turned flange adjacent to said sleeve flange, a lubricator within and held by said casing at the end of said sleeve, and a single spring acting between the flange of said lubricator casing and said spindle to hold the valve closed and the lubricator casing in position.

In testimony whereof, I have hereunto set my hand.

JAMES R. MOORE
